[57] **CLAIM**

The hands-free air compressor, as shown and described in the drawings.

DESCRIPTION

FIG. 1 is a perspective view of the air compressor of this invention;

FIG. 2 is a top view of the air compressor of this invention;

FIG. 3 is a front view of the air compressor of this invention;

FIG. 4 is a right side view of the air compressor of this invention, the opposite side view being a mirror image;

FIG. 5 is a rear view of the air compressor of this invention; and,

FIG. 6 is a bottom view of the air compressor of this invention.

The left side view is substantially similar to the right side view and is not shown.

The broken line showing of a partial power cord in FIGS. 1, 3-6 and a depression in FIGS. 1, 2 and 5, is for illustrative purposes only and forms no part of the claimed design.
